UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,140, dated March 6, 1888.

Application filed January 26, 1888. Serial No. 262,064. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of the figure A and similar figures repeated over the surface of the carpet, as shown. The figure A is very irregular

in outline and is composed of a number of convoluted forms. Similar forms of a lighter character occur on the outside of the figure. These convoluted forms overlie one another in different positions. The whole figure presents the appearance of a cloud mass. 20

What I claim as new, and desire to secure 25 by Letters Patent, is—

1. The design for carpets, consisting of the figure A, substantially as shown.
2. The design for carpets, consisting of the figure A and the other figures, substantially 30 as shown.

JAS. L. FOLSOM.
